Primary Examiner — T. Chase Nelson*Assistant Examiner* — Mark Cavanna(74) *Attorney, Agent, or Firm* — Reinhart Boerner Van Deuren s.c.(57) **CLAIM**

We claim the ornamental design for a multiple capnography display, as shown and described.

DESCRIPTION

FIG. 1 is a perspective view of a multiple capnography display showing my new design;
 FIG. 2 is a front view of the claimed design of FIG. 1;
 FIG. 3 is a rear view of the claimed design of FIG. 1;
 FIG. 4 is a left side view of the claimed design of FIG. 1;
 FIG. 5 is a right side view of the claimed design of FIG. 1;
 FIG. 6 is a top view of the claimed design of FIG. 1; and,
 FIG. 7 is a bottom view of the claimed design of FIG. 1.
 The ornamental design which is claimed is shown in solid lines in the drawings. The broken lines shown in the drawings are for illustrative purposes only and form no part of the claimed design.

1 Claim, 5 Drawing Sheets(56)
